UNITED STATES PATENT OFFICE.

WILLIAM JAMES NOBLE, OF PHILADELPHIA, PENNSYLVANIA, ASSIGNOR OF ONE-HALF TO ELLA McGINNIS, OF PRINCETON, NEW JERSEY.

MAIL DELIVERING AND CATCHING DEVICE.

SPECIFICATION forming part of Letters Patent No. 708,390, dated September 2, 1902.

Application filed April 10, 1902. Serial No. 102,244. (No model.)

To all whom it may concern:

Be it known that I, WILLIAM JAMES NOBLE, a citizen of the United States, and a resident of Philadelphia, in the county of Philadelphia and State of Pennsylvania, have invented a new and Improved Mail Delivering and Catching Device, of which the following is a full, clear, and exact description.

The object of the invention is to provide a new and improved mail delivering and catching device which is simple and durable in construction, very effective in operation, and arranged to positively deliver a mail pouch or bag from a passing train to a track-station and simultaneously cause an outgoing mail pouch or bag to be picked up by the train from the station.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement as applied, parts being shown in section. Fig. 2 is a cross-section of the same. Fig. 3 is a like view of the same with parts in position after exchange of the mail-pouches from the station to the mail-car and from the mail-car to the station, and Fig. 4 is a perspective view of a mail-pouch holder.

Lengthwise of the door-opening A' and at the outside of the mail-car A is arranged a longitudinally-extending pivot B, on which is mounted to swing up and down and to slide longitudinally an arm C, provided at its outer end with a suspending device in the form of a hook D for the reception of one of the spring-hooks E, held on the ends of a flexible tie F, such as a rope, the tie being adapted to form a loop or noose F' for engaging the middle of the mail bag or pouch G to be delivered from the mail-car A to the track-station H, as hereinafter more fully described.

The flexible tie F extends through spaced apertures in a tie-plate F² to form the loop F' at the inner side of the tie-plate, as plainly shown in Fig. 4. On the said tie is formed a

knot or stop F³, adapted to abut against the tie-plate at the outer face thereof to allow the operator to draw the tie taut and close the loop F' tightly around the mail bag or pouch 55 at or near the middle thereof to securely hold the pouch in position on the tie.

On the arm C between the hook D and the pivot B is arranged a receiving device I, adapted to receive the tie F', similar to the tie F, and arranged to carry the mail pouch or bag G' to be passed from the track-station H to the mail-car A. The tie F' is provided with a tie-plate F² and a stop F³, the same as the tie F, and the ends of the said tie F' are 65 provided with the hooks E, of which the upper one is adapted to engage a suspending device in the form of a hook J, formed on the outer end of an arm K, fulcrumed on and mounted to slide on the pivot L, held longitudinally in the framework N of the track-station H. The arm K carries a receiving device O, similar to the receiving device I and adapted to receive the tie F, suspended from the hook D of the arm C on the mail-car A 75 at the time the latter passes the station H. The lower hook E on the tie F' is adapted to be hooked onto a hook P of a spring-arm P', attached to the framework N, so that the mail-pouch G' and its tie is held against 80 swaying caused by the wind when suspended on the hook J.

The arm C of the mail-car A is provided with an undercut lug C' forward of the fulcrum or pivot B, and this lug C' is adapted 85 to be engaged by a catch Q, fulcrumed on the car A at the top beam of the opening A'. The arm C is provided with an inward extension C² under the control of the operator in the mail-car A to swing the arm C into an 90 active position, as shown in Figs. 1 and 2, the arm being temporarily locked in this position by the catch Q engaging the lug C'—that is, during the time the car approaches the track-station H.

Upon the end of the extension C² is a pin C³, adapted to be engaged by a link Q' on the catch Q to lock the latter and the arm C in a folded position on the outside of the car at the time the device is not in use, so that the 100 arm C does not unduly project from the side of the car to strike objects along the track.

The other arm K is provided with a catch S to hold it in an active position, as shown in Figs. 1 and 2, and this catch S is held on the framework N and is adapted to engage the 5 free end of an extension K' of the arm K.

The arms C and K are held free to slide on the pivots B and L, as previously mentioned, but are held normally against such sliding motion by springs T, coiled on the said pivots B and L and pressing opposite sides of the arms C and K to allow the latter to slide in either direction on their pivots against the tension of the corresponding spring at the time a longitudinal pull is exerted on the 15 arms C and K by the ties F F⁴, suspended thereon, and be caught in the opposite receiving device O or I at the time the mail-car passes the station H. When this sliding movement of the arms C and K takes place, 20 the lug C' moves from under the catch Q and the extension K' moves away from the catch S, so that the arms are unlocked and are now free to swing downward by their own weight and that of the mail-pouches G' or G, caught 25 up and suspended from the receiving devices I and O. Each receiving device I and O is provided on each side with a guideway U to guide the corresponding tie F or F⁴ to its receiving device. Each of the receiving devices I and O is in the form of a U-shaped 30 spring secured at its middle to the top surface of the arms C or K, the ends of each spring forming jaws normally closed and adapted to be opened by pressure of the tie F or F⁴. Thus when a tie is forced through 35 the jaws of the U-shaped spring the tie passes into the opening of the receiving device, and as this opening is smaller than the ends of the tie it is evident that the tie is held in position in the receiving device until removed 40 therefrom by force exerted by the operator in pulling the tie again outward between the jaws formed by the spring.

Pins U' may be arranged on the under side 45 of the guideways U to engage the ties F F⁴ at the time the arms C and K swing down after the bags are exchanged. (See Fig. 3.) When the arms C and K are locked in working position, as shown in Figs. 1 and 2, then 50 the hook D stands above the receiving device O and the hook J stands above the receiving device I at the time the car passes the station, the arm C and K being so shaped, however, as to readily clear each other on the car 55 passing the station, as will be readily understood by reference to Fig. 2.

The operation is as follows: The pouch G' is suspended by its tie F⁴ from the hook J and is held against swaying in the wind by 60 engaging the lower hook E with the hook P, the arm K being locked in an active position by the extension K' engaging the catch S. Now the operator in charge of the mail-car A suspends the tie F, carrying the pouch G, from the hook D and then swings the arm C 65 into a normal active position, as shown in Figs. 1 and 2, the arm being locked in this

position by the catch Q engaging the undercut lug C'. The tie F⁴ is now in alignment with the guideways U, leading to the receiving device I, held on the arm C of the approaching mail-car, while the tie F, carrying the mail-pouch G, is in alignment with the guideways U for the receiving device O, so that when the car passes the station H the 70 ties F⁴ and F are guided by the guideways U to the receiving devices I and O and are forced through the jaws thereof to the inside thereof and drawn partly through the same until the mail bags or pouches G G' abut against the 75 under side of the guideways, so as to exert a back pull on the ties to pull the open hooks E out of the hooks J and D, the incident pull on the said ties causing a longitudinal sliding of the arms C and K, so that the lug C' 80 moves out of engagement with the catch Q and the extension K' moves out of engagement with the catch S. Now as soon as this takes place the arms C and K swing downward by their own weight and that of the ties 85 F⁴ and F and the pouches G' and G, carried thereby, it being understood that the pouch G is now held by the device on the station H and the pouch G' is held by the device on the mail-car, so that the attendant in charge 90 thereof can pull this pouch G' to the inside of the car and detach the tie from the receiving device I, as previously explained. In a similar manner the man in charge of the station H disengages the tie F from the receiving device O, carrying the pouch G. The pouches are now exchanged and the catching and delivering devices are in an unlocked 95 position, ready to be reset when required.

The spring-hook E on the end of the tie F for engaging the hook J is preferably somewhat stronger than the other spring-hook E engaging the hook P on the spring-arm P', so that the tie is first released from the hook P' before it is disengaged from the hook J.

Having thus described my invention, I claim as new and desire to secure by Letters Patent—

1. A mail delivering and catching device, comprising arms mounted to swing and to slide lengthwise on their pivots, one of the arms being located on a car and the other on a track-station, a hook on the free end of each arm, to suspend a pouch, and a receiving device on each arm, for receiving a pouch, the receiving device being arranged between the hook and the pivot of the arm, as set forth.

2. A mail delivering and catching device, comprising arms mounted to swing and to slide lengthwise on their pivots, one of the arms being located on a car and the other on a track-station, a hook on the free end of each arm, to suspend a pouch, a receiving device on each arm, for receiving a pouch, the receiving device being arranged between the hook and the pivot of the arm, and catches for engaging the arms, to hold the same set in pouch-exchange position, as set forth.

3. A mail delivering and catching device,

- comprising arms mounted to swing and to slide lengthwise on their pivots, one of the arms being located on a car and the other on a track-station, a hook on the free end of each arm, to suspend a pouch, a receiving device on each arm, for receiving a pouch, the receiving device being arranged between the hook and the pivot of the arm, and catches for engaging the arms, to hold the same set in pouch-exchange position, the catches being arranged to release the arms on the latter sliding longitudinally on their pivots, as set forth.
4. A mail delivering and catching device, comprising arms, of which one is mounted to swing and to slide longitudinally on a car and the other is similarly mounted on a track-station, a suspending device on each arm for supporting a pouch, a receiving device on each arm for receiving the pouch, the suspending device on one arm and the receiving device on the other arm lying in the same vertical plane, at the time the parts are set in pouch-exchanging position and the car passes the station, and a hook fixed at the track-station and adapted to be engaged by the lower end of the pouch-suspending device, as set forth.
5. A mail delivering and catching device, comprising arms mounted to swing and to slide lengthwise on their pivots, one of the arms being located on a car and the other on a track-station, a hook on the free end of each arm, to suspend a pouch, a receiving device on each arm, for receiving a pouch, the receiving device being arranged between the hook and the pivot of the arm, catches for engaging the arms, to hold the same set in pouch-exchange position, and springs pressuring the arms at their fulcrums, to hold the arms yieldingly in position for the catches to engage the arms, as set forth.
6. A mail delivering and catching device, provided with a suspension device for a pouch, and comprising a flexible tie, and a tie-plate having spaced apertures for the passage of the tie to form a loop or noose in the tie at one side of the tie-plate, as set forth.
7. A mail delivering and catching device, provided with a suspension device for a pouch, and comprising a flexible tie, a tie-plate having spaced apertures for the passage of the tie to form a loop or noose in the tie at one side of the tie-plate, and a stop on the tie, to abut against the face of the tie-plate, as set forth.
8. A mail delivering and catching device, provided with a suspension device for a pouch, and comprising a flexible tie, a tie-plate having spaced apertures for the passage of the tie to form a loop or noose in the tie at one side of the tie-plate, and open spring-hooks on the ends of the tie, as set forth.
9. A mail delivering and catching device, comprising arms mounted to swing and to slide lengthwise on their pivots, one of the arms being located on a car and the other on a track-station, a hook on the free end of each arm, to suspend a pouch, a receiving device on each arm, for receiving the pouch, the receiving device being arranged between the hook and the pivot of the arm, and guideways leading to the entrance ends of the receiving devices, as set forth.
10. A mail delivering and catching device, comprising arms mounted to swing and to slide lengthwise on their pivots, one of the arms being located on a car and the other on a track-station, a hook on the free end of each arm, to suspend a pouch, and a receiving device on each arm, for receiving the pouch, the receiving device being arranged between the hook and the pivot of the arm, the said arms being arranged to clear each other on the car passing the station and the hook of one arm standing above the receiving device of the other arm, at the time the car passes the station, as set forth.
11. A mail-bag delivering and catching device, comprising two arms, one on a car, and the other on a track-station and each mounted to swing and to slide longitudinally, and provided with a hook at its free end and with a receiving device between the hook and pivot, springs on the pivots of the arms and pressing on opposite sides of the said arms, catches for holding the arms in operative positions and flexible pouch-ties provided with spring-hooks for engaging the hooks of the said arms, as set forth.
12. A mail-bag delivering and catching device, comprising two arms, one on a car and the other on a track-station and each mounted to swing and slide longitudinally, said arms being provided with a hook at its end, a receiving device between the hook and pivot, a guideway leading to the receiving device, and a pin on the under side of the guideway, springs for holding the arms normally from sliding, catches for holding the arms in operative positions, and flexible pouch-ties provided with spring-hooks at their ends, as set forth.
- In testimony whereof I have signed my name to this specification in the presence of two subscribing witnesses.
